UNITED STATES PATENT OFFICE

TRACY F. BRACKETT, OF HIGHLAND PARK, MICHIGAN

PORTABLE ABRADING AND POLISHING MACHINE

Application filed August 28, 1931. Serial No. 559,993.

My invention relates to improvements in portable sanding and polishing machines.

One of the objects of my invention is to provide a portable machine which is particularly adaptable for operating on curved or irregular surfaces.

A further object is to provide a portable machine having an abrading or polishing member which when applied to the surface to be treated, will conform itself to curves or irregularities in the surface so as to have a much greater area of uniform contact with the work than is possible with the usual abrading and polishing wheels.

Other objects of my invention will appear hereinafter.

Referring to the accompanying drawing

Fig. 1 is a view in elevation of a portable abrading and polishing machine embodying my invention;

Fig. 2 is a sectional view on the line 2—2 of Fig. 1;

Figs. 3, 4 and 5 are detail sectional views of different forms of abrading and polishing elements which can be used in connection with my invention.

The usual abrading and polishing wheels which are in common use are, of course, circular in shape having only a very limited area of contact with the surface of the work which is being treated, and the treating of an extended surface or a surface greater than the area of contact is accomplished by moving the work and the wheel relatively to each other. This area of contact is very limited even though wheels are made flexible or yielding. This is particularly true in treating curved or irregular surfaces. The usual wheel cannot reach all portions of these surfaces and the pressure is not uniform throughout the area of contact, making it very difficult to grind or polish the work uniformly.

I propose to employ a flexible belt or band having an abrading surface and maintained in state of slackness or looseness whereby it will, when placed in contact with the work, adapt itself to the curves or irregularities in the surface by conforming to the contour thereof. I accomplish this by using an end-

less slack belt or band and propelling this belt in the line of itself in such manner that the centrifugal force developed forces the belt the working surface of the belt against a considerable portion of the area of the surface of the work.

In the present structure a suitable frame 1 is provided which supports the shafts 2 of belt supporting pulleys 3 and which also serves as a suitable enclosure or housing for the driving chain 4 and sprocket wheels 7. The housing is made in two sections, Fig. 2, which are joined together around their periphery by the bolts 5 so that access may be obtained to the interior of the housing when desired. The pulley shafts 2 are mounted in suitable bearings 6 formed in the frame housing and each shaft has a sprocket wheel 7 for the drive chain. Between the pulley shafts a suitable electric driving motor 8 is mounted. The motor has a shaft 9 extending through a suitable opening in the wall of the housing having at its end a pinion 10 in driving engagement with the chain, Fig. 1. This drives the pulley shafts 2 in the same direction at the same speed because the sprockets 7 are of the same size. The rear wall of the housing has upwardly and downwardly extending flanges 11 with vertical slots 12 therein, and screws 13 are passed through these slots and into the motor shell for clamping the motor shell to the frame. The slots 12 permit the motor and its pinion 10 to be adjusted relatively to the frame for the purpose of adjusting the tension on the drive chain. The motor shell has a downwardly extending flange 14 which conforms to the lower flange 11 of the frame housing to provide for the lower clamping screw 13. While I have shown an electric motor attached to the frame for driving the pulleys, it is obvious that a flexible shaft may be used. The shaft may be attached to the frame and connected to the pinion 10 for driving the chain.

The structure shown is intended as a portable unit and is provided with suitable handles 15 for the operator. One of these handles is placed in alignment with each

of the pulley shafts 2 so as to give the operator two points of control in handling the unit. For convenience of manufacture the handles are inserted in the ends of bushings 16 which are fitted over the projecting bearings 6 of the shafts 2 on the rear side of the frame. It is obvious, however, that the handles may be placed in any position upon the frame found to be best adapted for the purpose.

The pulley shafts 2 and the pulleys mounted thereon extends considerably beyond the frame a sufficient distance so that the frame will not interfere with the manipulation of the abrading belt in all directions with respect to the work. The belt pulleys 3 are spaced apart to provide space between them for the work. The pulleys have flanges 3' to prevent the belt from slipping laterally off of the pulleys. The belt A is endless and extends around both pulleys to provide driving contact with the pulleys. The length of the belt is greater than it would be if stretched tight around the pulleys so that the reaches or unsupported portions A' can bow outwardly under the action of centrifugal force developed when the belt is driven when the working portion of the lower reach A' is placed in contact with the surface of work to be treated, its flexibility permits it to conform to the surface of the work, this conformance being brought about by the centrifugal force developed in the belt. In Fig. 1 an irregular curved surface is indicated by the dotted line B, and the manner in which the belt conforms to its surface is indicated by the dotted lines A''.

The belt may be made up of several narrow sections placed side by side or it may be a single piece of the proper width for the purpose. The abrasive or polishing material may be applied directly to the outer surface of the belt or it may be carried on a separate strip 17, Figs. 3, 4 and 5 and the strip 17 applied to the outer surface of the belt by stitching or any other well known method of applying abrasives to polishing implements.

Figs. 3, 4 and 5 indicate several different types of abrasives used in abrading and polishing work. In Fig. 3 the abrasive is shown as a wire pile 18 on the fabric strip 17. In Fig. 4 the polishing surface shown has cloth polishing pads or loops 19 stitched at intervals 20 to the strip 17. Fig. 5 shows the abrasive, such as emery or carborundum 21, applied to the strip 17.

In a portable unit of this character the operator has almost universal movement of the unit in placing the belt in contact with the work, and, due to the slackness and flexibility of the belt it will readily adapt itself to this universal movement and conform itself to the curves or irregularities of the

surface which is being treated. The slack belt has a comparatively great area of contact with the surface being treated and the pressure on this surface will be practically uniform throughout the area thereof with the result much more uniform and efficient work can be performed at a much greater speed.

I am aware that changes and alterations may be made in the construction and arrangement of the parts without departing from the scope and spirit of the invention and I reserve the right to make such changes as fairly fall within the scope of the appended claims.

I claim:

1. In a device of the class described, a housing having fixed bearings therein, shafts journaled in said bearings and disposed in spaced relation and extending beyond said housing, sprockets fast on said shafts in said housing, an endless chain directed about said sprockets, mounting means on said housing intermediate said bearings, a driving motor, a sprocket on the shaft of the motor and meshed with said chain, means adjustably securing said motor on said mounting means whereby said motor may be moved to tension said chain, said motor driving said chain to impart rotative movement to said shafts, flanged pulleys fast on the portions of said shafts extending beyond said housing, and an endless flexible belt directed about said pulleys and of greater length than required to be stretched taut around the pulleys, said belt having an abrading surface on the outer face thereof, said belt being bowed outwardly by the centrifugal force developed during movement imparted to the belt whereby the abrading surface on the bowed portion of the belt may be engaged with and conformed to a surface to be abraded.

2. In a device of the class described, a housing having fixed bearings therein, shafts journaled in said bearings and disposed in spaced relation and extending beyond said housing, sprockets fast on said shafts in said housing, an endless chain directed about said sprockets, mounting means on said housing intermediate said bearings, a driving motor, a sprocket on the shaft of the motor and meshed with said chain, flanges on said housing intermediate said bearings and extending transversely of the housing, a bracket on the motor, means adjustably securing said bracket to said flanges to vary the position of said motor and the sprocket on the shaft thereof to tension said chain, said motor driving said chain to impart rotative movement to said shafts, flanged pulleys fast on the portions of said shafts extending beyond said housing, an endless flexible belt directed about said pulleys and of greater length than required to be

stretched taut around the pulleys, said belt having an abrading surface on the outer face thereof, handles on said housing extending therefrom in alignment with said shafts,
5 said handles being grasped to permit movement of said housing whereby a portion of the belt intermediate the pulleys bowed outwardly by the centrifugal force developed during movement imparted to the belt may
10 be engaged with and conformed to a surface to be abraded.
